UNITED STATES PATENT OFFICE.

ERICH H. LICHTENBERG, OF MILWAUKEE, WISCONSIN, ASSIGNOR TO KOEHRING COMPANY, OF MILWAUKEE, WISCONSIN, A CORPORATION.

WATER-MEASURING CONTROLLER FOR MIXERS.

Application filed September 30, 1925. Serial No. 59,714.

In the operation of concrete mixing machines today, where the concrete produced by the machine is required to be of definite predetermined quality, the mixing of each 5 batch of concrete that passes through the machine is timed. As a general thing the time necessary to produce a proper and efficient mix, assuming that the aggregates are properly proportioned, is from a minute to 10 a minute and a half.

For the purpose of insuring the production of a properly timed mix there is commonly used at this time a device known as the batchmeter. The first type of batchmeter 15 mentioned in the art was invented by me and is covered by Letters Patent #1,321,460, issued November 11, 1919, and improved types of such timing devices are exemplified by Letters Patent #1,532,277, issued April 20 7, 1925; #1,338,761, issued May 4, 1920; #1,451,483, issued April 10, 1923; and #1,370,497, issued March 1, 1921.

The batchmeter contrivance as a timing device controls the time for the discharge of 25 the mixer by the operation of the discharge chute, and said charge chute in some instances is manually operated on signal, and in other instances is mechanically operated by suitable devices for this purpose.

In the operation of all mixing machines 30 provision is made for supplying water to the mixer as a part of each batch of concrete produced. This water must be supplied in a definite quantity and at a predetermined 35 time, namely, when the solid aggregates are being charged into the mixer, and it is highly requisite that the water if possible, be in the mixer with the solid aggregates before the timed period of mixing commences.

The primary object of my invention, having 40 in view the above described method of timing mixed batches, and supplying water to a mixing machine, has been to design a water supply means which constitutes virtually 45 a batchmeter or timer, with suitable provision for controlling the length of the mixing period by a control of the flow of the water to the timing device which consists of a measuring tank batchmeter, in 50 practical effect and operation.

The invention involves additionally the interlocking of a timing device of the origi-

nal type above mentioned with operations of a mixer discharge actuating mechanism, charging skip mechanism, and water inflow 55 and outflow control valves having to do with the supply of the timing measured quantity of water to the batchmeter tank and from said tank, respectively.

In the accompanying drawings Figure 1 60 is a side elevation of a mixing machine embodying the invention.

Figure 2 is an end view of the machine looking toward the charging end of the drum with the loading skip and certain associated parts removed.

Figure 3 is a detail view showing the scale beam weighing devices for the batchmeter tank.

Figure 4 is a view of the float operated 70 valve mechanism in the stationary supply tank.

Figure 5 is a view of the supply tank and batchmeter tank and associated features considerably enlarged as compared with Figure 1, and showing the latter tank partly in section to bring out interior features.

Figure 6 is a sectional view of the batchmeter tank looking from a direction at right angles to Figure 5, the tank supporting 80 means being also depicted in part.

In the accompanying drawings there is a mixing machine which may be of a portable type mounted upon a suitable traction base susceptible of propulsion in different ways, 85 or a stationary plant, if desired, this being immaterial to the invention. The mixing machine embodies certain well known means of construction commonly employed and including the supporting framework 1, the drum 2, the main water tank 3, the loading skip 4 and the discharging chute 5. The loading skip 4 will be raised and lowered by conventional cable hoisting means 6 or any power mechanism that may be suitable for the purpose, and the discharging chute 5 may be manually operated, though in the drawings the same is illustrated as a power operated chute through the provision of an actuating shaft 7 having the actuating arm 8 connected by linkage 9 with a power device 10 for moving the chute from a non-discharging position, to a charging position, and vice-versa.

The power device 10 may be constructed in one of a number of different ways. In the present case I provide an operating shaft 11 having a gear 12 meshing with one of the 5 ring gears 13 of the drum 2 and constantly driven during the rotation of said drum. The shaft 11 has a worm 12^a cooperating with a worm gear 13^a provided with a worm 2 having a periphery of a special interrupted construction which is not a feature of the 10 present invention. The gear 13^a operates an arm 14 up and down when said gear 13^a is caused to cooperate by a worm 12^a with the trip 15. This up and down movement of 15 the arm 14 is transmitted to the arm 8 and shifts the chute 5 to the non-discharging and discharging positions as required.

The water tank 3 is supplied with water under pressure by a main line supply pipe 20 16 and I provide within the tank 3 a float control valve means seen in Figure 4, to maintain said water in the tank 3 at a constant level. Water is adapted to be conducted through a pipe 17 to a valve casing 18, 25 and therefrom through a pipe 19 to a batchmeter tank 20. The tank 20 has an opening in the upper end at 21 to receive the pipe 19, and sufficiently large so that the tank 20 may move vertically relatively to the pipe 30 19.

The batchmeter tank 20 is virtually a weighing tank and is mounted for vertical movement by being supported by links 21 which attach it to the framework 1 of the 35 machine, and by being supported by bar 22 the upper end of which is pivoted to the short lever arm of a weighing beam 23. The beam 23 is fulcrumed to the frame 1 by means of a pivot shaft 24 fastened to the 40 beam so as to turn as the beam rocks, and having the fixed arm 25 adapted to be rocked with the movement of the beam 23. The arm 25 is connected by a rod 26 to the trip 45 15 which controls the starting of the power device 10 which works the chute 5 on the scale beam 23 having the adjustable weight 27, adjustment of which controls the amount of water received and weighed by the tank 20.

50 At its lower end the tank 20 is provided with an outflow port 28 disposed above the water discharge pipe 29 which leads from the said port to the mixing drum 2. The passage of the water from the tank 3 to the 55 batchmeter tank 20 is controlled by any suitable means, that illustrated for example being a valve 30 in the casing 18, adapted to seat itself on the valve seat 31 so as to close the upper end of the pipe 19. The valve 30 is connected by an actuating rod 32 with a 60 trip bar 33 secured to the tank 20, there being a spring 34 between said bar 33 and an abutment 35 on the rod 32.

For controlling the passage of water out 65 of said tank 20 through its port 28, I pro-

vide a swinging valve 36 having an arm 37 connected with adjustable rod means 38 that is provided at its lower end with an actuating hook or abutment 39. The operating arm 37 for the valve 36 is carried by the 70 swing shaft 40 of the valve and said shaft has secured to it a spring arm 41 adapted to cooperate with a stationary arm 42 designed to close the valve 36 in a manner hereinafter described. The loading skip 4 75 carries at its pivotal support 43 an arm 44 fixed to said support which is a shaft, and said arm 44 has a roller 45 to engage the abutment 39 on the lower end of the rod means 38 previously referred to.

At the free end of the weighing arm of the scale beam of the lever 23 is a catch 46 adapted to engage, when raised, with a latch 47 suitably supported on the framework of the machine. The latch 47 has a weighted arm 48 so that it normally tends to become engaged with the catch 46 by gravitation of the arm 48. Moreover, the latch 47 is connected with a trip rod 49 having a cam 50 on its free end and a catch 51 adjacent to said cam. A roller 52 mounted on the side of the skip 4 is adapted to be engaged with the catch 51 of the trip rod 49 as will now shortly be described.

With the foregoing organization of the parts of my machine I obtain the following operation, describing a complete cycle of action of the parts.

We shall assume for the moment that the batchmeter tank 20 is full, or rather contains a charge of water ready to be fed to the discharge pipe 29 so as to enter the drum 2. Under these conditions the weighing beam 23 and trip parts are in the full line position of Figure 3, and the trip 15 has been previously operated to cause the power device 10 to throw the chute 5 to its discharging position, in which it inclines downwardly and outwardly, instead of as shown in Figure 1, drum being discharged.

It is assumed further that the skip 4 has been loaded with solid aggregates to be charged into the drum 2 with the aforesaid water. The valve 30 (see Fig. 2) is closed down.

The operator of the machine now causes the skip 4 to rise and when said skip reaches a point about 20° above the sub-grade the roller 45 actuates the trip rod 38 and swings the valve 36 upward to open position. The water in the tank 20 immediately drains therefrom and is charged into the drum 2. The tank 20 however, still remains down at its lower limit of movement because the beam 23 is locked up at its left hand end by the latch 47. Meanwhile the skip 4 is rising and reaches its uppermost limit of movement at which it charges the solid aggregates therein, into the drum 2. Thereafter the skip 4 is lowered, but its roller 52 has

previously engaged the catch 51 of the trip rod 49 and as the skip begins to go down it pulls on the rod 49 and disengages the latch 47 from beneath the catch 46 of the scale beam 23. Immediately the weight 27 becomes operative to rock the beam 23 and raise the tank 20 for the reception of a fresh charge of water. At this time the part 15 causes action of the power drive mechanism 10 to restore the chute 5 to non-discharging position. This is the moment, namely, when all of the parts of aggregates to be mixed are charged into the mixer, from which I time the mixing of the batch thus introduced. At this particular time of commencement of the mixing period controlled by my invention, the discharging chute 5 and cooperating parts are in the positions of Figure 1 with the chute locked against discharging movement.

When the tank 20 was raised by the weight 27 the valve 30 was unseated and water was immediately supplied to the tank 20 from the tank 3 and continues to pass into the tank 20 at a measured rate of flow which, for the purposes of this description, we will say requires one minute in which to charge the tank 20 with the required water for a batch of solid aggregates to be mixed in the drum 2. When the said minute has elapsed the tank 20 promptly overbalances the weight 27, and said tank is lowered by rocking the beam 23 and raising the weight 27, said beam 23 again becoming locked up by the latch 47. The lowering of the tank 20 denotes the end of the mixing period required for the proper mixing of the aggregates and the rocking of the beam 23 as stated rocks the arm 25 at the fulcrum of the beam, which arm 25 pulls on the trip rod 26 and actuates the trip 15 to start the power device 10 into action, which power device moves the chute 5 down into its discharging position, thereupon the contents of the drum 2 are discharged automatically at the lapse of the time fixed as the mixing period.

It is to be noted that when the scale beam 23 was released from the latch 47 permitting the weight 27 to drop, and raising the tank 20, the spring arm 41 struck the abutment arm 42 and caused the swing valve 36 to close the outflow port at the lower end of the tank. This is necessary because otherwise, the tank 20 could not be filled.

The trip rod 26 controlling the power device 10 likewise controls an arm 54 to actuate a bell tapper 55 cooperating with the signal bell or indicator 56 so that as the tank 20 moves down, determining the end of the mixing period the arm 54 will move the tapper 55 and ring the bell 56 so as to notify the operator of the machine that the batch is ready to be discharged. This method of signalling may be used as an independent means by itself to notify the operator of the

machine at the end of the mixing period so that he may actuate the operating means for the discharging chute 5 and discharge the drum 2. Or the signal 56 may be used in conjunction with the power operating device 10 previously described.

It is evident from the foregoing that where the flow of the tank 3 to the tank 20 is constant the time when the tank 20 moves to control the batchmeter functions thereof, may be varied to slightly increase or shorten the time of the mixing period, by adjustment of the weight 27. Or I may provide in the length of the pipe 17 a flow controller in the form of a valve device 57 having an associated indicator 58 and indicating dial 59. By adjusting the valve 57 the flow of the water through the pipe 17 to the tank 20 may be increased or decreased and the time factor incident to the filling of the tank 20 with the proper charge of the water may be thus controlled. Moreover, the indicator 58 may be locked against movement so that there can be no tampering with this time factor control under which conditions unauthorized lowering of the mixing period cannot be done. Naturally, it might be an objective of the user of the mixing machine to work the machine faster than permissible for effective mixing, and this is prevented by the protective features of my mechanism just described.

The discharging chute 5 may be raised to non-discharging position by action of the trip 15 cooperating with the power device 10 to start the latter into operation, when the scale beam is released as the skip 4 moves downwardly. Under these conditions the trip 15 would be double acting.

It is noted that the connection 38 involves a coiled spring element 60 at the upper end intermediate the rod 38 and the valve closing member 37. Under these conditions therefore while the action of the spring 60 is sufficient to enable the members 45 and 38 to open the valve 36 at the proper time, when the tank 20 is raised and the valve 30 opened, the spring 60 will not offer much resistance to the closing movement of the valve 36 under the action of the closing spring cam 41.

The means 10 referred to herein for actuating the discharge chute 5 is a type of known means set forth in U. S. patent of Webb, No. 1,628,378, issued May 10, 1927.

Having thus described my invention, what I claim as new and desire to secure by Letters Patent, is:

1. In combination, a concrete mixer, water supply means therefore, and water measuring means for timing the period of mixing of aggregates in the mixer said measuring means communicating with the water supply means and controlling the flow therefrom.

2. In combination, a concrete mixer, water measuring mechanism for determining the quantity of water to be introduced into the mixer with each batch of solid aggregates, and constituting a batchmeter controlling the period of mixing of the batch in the mixer.
3. In combination, a concrete mixer, water measuring mechanism for determining the quantity of water to be introduced into the mixer with each batch of solid aggregates, a mixing time period indicator, and means intermediate the measuring mechanism and indicator to operate the latter from the former.
4. In combination, a concrete mixer, water measuring mechanism for determining the quantity of water to be introduced into the mixer with each batch of solid aggregates comprising a tank, and a mixer discharger operated under the control of movement of the tank.
5. In combination, a concrete mixer, water weighing means to supply water to the mixer, mixer charging means, and automatically operating devices between the weighing and charging means so one is controlled from the other.
6. In combination, a concrete mixer, water weighing means to supply water to the mixer, mixer charging means, and automatically operating devices between the weighing and charging means so one is controlled from the other and a timer indicator for the mixing period of action of the mixer controlled from said weighing means.
7. In combination, a concrete mixer, water measuring means to supply water to the mixer, mixer charging means, and automatically operating devices between the measuring and charging means so one is controlled from the other and a timer indicator for the mixing period of action of the mixer controlled from said measuring means.
8. In combination, a concrete mixer, water weighing means to supply water to the mixer, mixer charging means and a mixing period controller mechanism operable from the weighing means.
9. In combination, a concrete mixer, a water supply, a water measuring tank, valve means controlling passage of water from the supply to the tank, and from the tank to the mixer, and a mixing period time controlled mechanism operable incident to action of the valve means controlling passage of water from the tank to the mixer.
10. In combination, a concrete mixer, discharge means therefor, water supply means for the mixer, and means to effect operation of the discharge means from the water supply means.
11. In combination, a concrete mixer having discharge means therefor, water supply means for the mixer acting as a batchmeter, and means to start the discharge means operation controlled from the water supply means.
12. In combination, a concrete mixer, discharge means therefor, water supply means for the mixer, acting as a batchmeter, and means to control the operation of the discharge means from the water supply means, and means to vary the flow of the water to said supply means to correspondingly vary the time of operation of the discharge means.
13. In combination, a concrete mixer, discharge means therefor, water supply means for the mixer, and means to control the operation of the discharge means from the water supply means, and a charging device controlling operation of the water supply means.
14. In combination, a concrete mixer, discharge means therefor, water supply means for the mixer, means to start the discharge means operating controlled from the water supply means, a device to charge solid aggregates into the mixer, and means to control the return of the water supply means, and thereby the discharge means, between the charging device and water supply means.
15. In combination, a concrete mixer, water charging means acting as a batchmeter therefor, and means for timing the period of mixing of aggregates in the mixer from said water charging means.
16. In combination, a concrete mixer, water charging means therefor, means for timing the period of mixing of aggregates in the mixer by the quantity of water handled by said water charging means, and means to vary the flow of water from the water supply means to the charging means, to vary the timing action of the last means.
17. In combination, a concrete mixer, water measuring mechanism for determining the quantity of water to be introduced into the mixer with each batch of solid aggregates, and a mixer discharger operated under the control of the water handled by said measuring mechanism, and a charging skip for controlling the operation of the measuring mechanism.
18. In combination, a concrete mixer, water charging means therefor, comprising a movable water tank, and means actuated by movement of said tank for governing the time of the effective mixing period of concrete in the mixer.
19. In combination, a concrete mixer, water charging means therefor, comprising a movable water tank, means actuated by movement of said tank for governing the time of the effective mixing period of concrete in the mixer, comprising a mixer discharge, and parts operated from the tank to set said discharge into action.
20. In combination, a concrete mixer, water charging means therefor, comprising a

- movable water tank, means actuated by movement of said tank for governing the time of the effective mixing period of concrete in the mixer, and a solid aggregates charger 5 controlling certain movement of the tank.
21. In combination, a concrete mixer, water charging means therefor, comprising a movable water tank, means actuated by movement of said tank for governing the 10 time of the effective mixing period of concrete in the mixer, and a solid aggregates charger adapted to empty the tank, with automatic means to close the emptying part of the tank.
22. In combination, a concrete mixer, water charging means therefor, comprising a movable water tank, means actuated by movement of said tank to governing the time of the effective mixing period of concrete in 15 the mixer, a solid aggregates charger adapted to empty the tank, with automatic means to close the emptying part of the tank, and weight means to raise the tank after emptying, with means to supply a fresh charge of 20 water to the tank when raised.
23. In combination, a concrete mixer, water charging means therefor, comprising a movable water tank, a valve to empty the tank, a valve to supply water to the tank, a charging device to open the first valve, and a means to open the second valve on movement of the tank.
24. In combination, a concrete mixer, water charging means therefor, comprising a movable water tank, a valve to empty the tank, a valve to supply water to the tank, a charging device to open the first valve, a means to open the second valve on movement of the tank, and a mixing period time 30 controlled device operable from the tank.
25. In combination, a concrete mixer, a water tank arranged to supply water to said mixer, means movably supporting said water tank, a discharge chute for the mixer, means 35 for operating said discharge chute, and means operated by movement of said water tank to cause the operating means for the discharge chute to go into action.
26. In combination, a concrete mixer, a water tank adapted to receive a predetermined quantity of water, discharge means for the mixer, means to control said discharging means to prevent it from operating until a predetermined mixing time has 40 elapsed which time corresponds with the predetermined time in which the water tank will be filled for dispensing water to the mixer, and means intermediate the water tank and the means which controls the discharging means whereby the movement of the said tank will govern the action of the latter.
27. In combination, a concrete mixer, a discharge therefor, means to charge solid aggregates into the mixer, a water tank ar- 45 ranged to supply water to the mixer, means supporting said water tank so that it will move when a predetermined quantity of water has been received thereby in a predetermined time and means adapted to be actuated after the predetermined time required for filling said tank to set into action the discharge means for mixer, whereby the tank acts as a batchmeter. 70
28. In combination, a concrete mixer, solid aggregates charging means for the mixer, means whereby the mixer may be discharged, and a water tank for supplying water to the mixer and constituting a batchmeter controlling the discharge means. 75
29. In combination, a concrete mixer, means for discharging the same, a movably supported water tank, water supply means for the tank adapted to supply a predetermined quantity thereto to cause movement of the tank, means operated from the tank for cutting off the supply of water thereto, solid aggregates charging means for the mixer, means for connecting the last means with the water tank to cause the water to 80 pass from the latter to the mixer, and means for causing the water tank to automatically cause commencement of flow of water thereto after it has been emptied. 85
30. In combination, a concrete mixer, discharging means therefor, solid aggregates charging means for the mixer, a water tank to supply the mixer, means for supplying water to said water tank and causing it to move after a predetermined charge of water 90 is received thereby, means for setting the discharging means of the mixer into action as an incident to the movement of said tank, and means for opening the tank to supply its water to the mixer operable by the solid 95 aggregates charging means, together with normalizing means for the various parts. 100
31. In combination, a concrete mixer, means for discharging the said mixer, a water tank, water supply means for said 110 tank, scale-beam and weight means for governing the amount of water which will be received by the tank for a charge of water for the mixer and operable by the tank, valve means to cut off the supply of water 115 to the tank as an incident to said scale-beam and weight means, a solid aggregates charging skip for the mixer and means intermediate the water tank and said skip for causing flow of the contents of the tank to the 120 mixer at a certain point in the movement of the skip.
32. In combination, a concrete mixer, a water tank to supply water thereto and having a valve, controlling passage of the water 125 to the mixer, a charging skip for the mixer to load solid aggregates thereinto, an operating rod connected with said valve, means on the charging skip arranged to engage and actuate said rod at the beginning of move- 130

ment of the skip to cause flow of water from the tank to the mixer substantially throughout the movement of the skip, and means controlling refilling of the tank when 5 emptied.

33. In combination, a concrete mixer, a water tank to supply water thereto and having a valve controlling passage of the water to the mixer, a charging skip for the mixer 10 to load solid aggregates therewith, an operating rod connected with said valve, means on the charging skip arranged to engage and actuate said rod at the beginning of movement of the skip to cause flow of water from 15 the tank to the mixer substantially throughout the movement of the skip, and means controlling refilling of the tank when emptied, and a resilient means intermediate said rod and said valve substantially as described.

34. In combination, a concrete mixer, a water tank to supply water thereto and having a valve, controlling passage of the water to the mixer, a charging skip for 20 the mixer to load solid aggregates therewith, an operating rod connected with said valve, means on the charging skip arranged to engage and actuate said rod at the beginning of movement of the skip to cause flow of 25 water from the tank to the mixer substantially throughout the movement of the skip, and means controlling refilling of the tank when emptied, means movably supporting 30 the water tank comprising counterbalance

weight device, a discharge for the mixer, 35 means for controlling said discharge operated incident to movement of the water tank, together with resetting means permitting the water tank to be refilled and operated from the loading skip. 40

35. In combination, a concrete mixer, water charging means for timing the period of mixing of aggregates in the mixer, a source of water supply communicating with 45 said charging means, and means intermediate the charging means and said source for regulating the water flow to the charging means.

36. In combination, a concrete mixer, water charging means for timing the period 50 of mixing of aggregates in the mixer, a water supply source communicating with said charging means, and valve means intermediate the charging means and said source 55 for regulating the rate of flow of water to the charging means to predetermine the period of mix of the aggregates.

37. In combination, a concrete mixer, water measuring means for timing the period of mixing of aggregates in the mixer, 60 a water supply source communicating therewith, and valve means intermediate the measuring means and said source operable by the measuring means to cut off the flow 65 of the water from the latter after a predetermined period of mix.

In testimony whereof I affix my signature.
ERICH H. LICHTENBERG.
